UNITED STATES PATENT OFFICE.

SAMUEL B. COCHRAN, OF GLEN EASTON, WEST VIRGINIA.

WRENCH.

No. 836,437.

Specification of Letters Patent.

Patented Nov. 20, 1906.

Application filed June 30, 1906. Serial No. 324,176.

To all whom it may concern:

Be it known that I, SAMUEL B. COCHRAN, a citizen of the United States of America, residing at Glen Easton, in the county of Marshall and State of West Virginia, have invented certain new and useful Improvements in Wrenches, of which the following is a specification, reference being had therein to the accompanying drawings.

10 This invention relates to wrenches; and its object is to provide a device of this character of simple and inexpensive construction capable of being readily manipulated to adjust it to working position and to release and disengage the opposing jaws.

15 The construction of the improvement will be fully described hereinafter in connection with the accompanying drawings, which form a part of this specification, and its novel 20 features will be defined in the appended claims.

In the drawings, Figure 1 is a side elevation of a wrench embodying the invention. Fig. 2 is a front elevation of the same. Fig. 25 3 is a sectional view on the line $x-x$ of Fig. 2. Fig. 4 is a view in perspective of the operating-lever of the wrench, and Fig. 5 is a perspective view of the housing constituting the movable jaw of the wrench.

30 The reference - numeral 1 designates a shank provided with a handle 2 at one end and an integral curved jaw 3 at its opposite end, said jaw serving as the fixed member of the wrench. Upon the shank 1 is slidably 35 supported a frame or housing comprising side bars 4 and 5, connected at their lower ends by a cross-bar 6 and at their upper ends by an integral jaw 7, the bar 6 and jaw 7 being formed with elongated openings 8 for the 40 passage of the shank.

The front side 4 of the housing is formed with a vertically-disposed slot 9 for the purpose hereinafter mentioned, and the jaws 3 and 7 are recessed for the reception of ser- 45 rated gripping-blocks 10.

The numeral 11 designates a lever provided with a yoke 12 and bent at the point 13 to project the yoke laterally to a position at a right angle to the handle portion of the 50 lever. The lever extends through the slot 9 of the housing, and the shank 1 extends through said yoke, as shown in Figs. 1 and 3, the opening in the yoke being of sufficient size to permit a limited tilting movement of

the yoke upon the shank by means of the 55 lever.

A coil-spring 14 encircles the shank 1 with- 60 in the housing, the lower end of said spring resting on the cross-bar 6, while its upper end bears against a washer 15, the upper face of 65 which is beveled, as shown. The opening in this washer 15 is of such size as to permit it to tilt slightly upon the shank.

Interposed between the yoke 12 and the washer 15 are a plurality of washers 16, four 70 being shown in the drawings. The inner surfaces of the end walls of these washers 16 adjacent to the lever 11 are cut away to provide centrally-projecting teeth 17, which normally engage the contiguous side of the 75 shank and bite against the same under the pressure of the spring 14. The beveled upper face of the spring-supported washer 15 causes the washers 16 to maintain the inclined positions shown in the drawings.

The utility and operation of the wrench will be readily understood. When the locking-washers are in the position shown, the movable jaw is locked upon the shank. By depressing the lever 11 the locking-washers 80 are turned to a horizontal position, the spring 14 being compressed by the pressure upon the washers 15 and 16, thus disengaging the teeth of the locking-washers from the shank 1 and permitting the movable jaw to be ad- 85 justed to any desired position, after which the lever is released to allow the spring to again lock the movable jaw.

It will be noted that the several washers 16 90 act simultaneously and insure a quick and positive frictional engagement of the teeth 17 with the shank.

The wrench is designed for use either as a nut-wrench or a pipe-wrench, and the location of the operating-lever renders the device 95 a simple and convenient implement.

What I claim, and desire to secure by Letters Patent, is—

1. A wrench comprising a shank provided with a fixed jaw, a frame slidably arranged on said shank, and provided with a movable jaw, a lever having a yoke surrounding the shank, a coil-spring surrounding the shank, a washer resting on said spring and having a beveled face, and a plurality of locking-washers formed with projecting teeth to engage the shank.

2. The combination with a shank provided

with a fixed jaw, of a frame or housing carrying a movable jaw, said frame or housing being movable on the shank, a lever formed with a yoke surrounding the shank, and bent 5 adjacent to said yoke, a coil-spring surrounding the shank, and resting on the cross-bar of the housing, a washer on the shank resting on the upper end of said spring, and having its upper face beveled, and a plurality of lock-
10 ing-washers on the shank between the yoke

and beveled washer, each of said locking-washers being cut away at one side of its inner surface to provide a projecting tooth.

In testimony whereof I affix my signature in the presence of two witnesses.

SAMUEL B. COCHRAN.
